UNITED STATES PATENT OFFICE.

GEORGE A. FINDER, OF CHICAGO, ILLINOIS, ASSIGNOR, BY MESNE ASSIGNMENTS, TO FINDER & URBANEK, INC., OF CHICAGO, ILLINOIS, A CORPORATION OF ILLINOIS.

REED TRIMMER.

Application filed August 2, 1924. Serial No. 729,852.

To all whom it may concern:

Be it known that I, GEORGE A. FINDER, a citizen of the United States, residing at Chicago, in the county of Cook and State 5 of Illinois, have invented certain new and useful Improvements in Reed Trimmers, of which the following is a specification.

This invention which relates to a device 10 for trimming reeds, such as are commonly used in wind instruments, is concerned with numerous features of construction having to do with simplicity, strength, dependability, etc. Objects such as these, as well as others, will more fully hereinafter appear.

15 An exemplification of my invention is set forth in the accompanying drawing in the manner following:

Figure 1 is an enlarged plan view of the present trimmer, together with a reed inserted for treatment;

Fig. 2 is a side elevation of the trimmer;

Fig. 3 is a longitudinal section therethrough taken on line 3-3 of Fig. 1; and

Fig. 4 is a detail bottom plan of the head 25 end of the device.

The present trimmer is preferably formed from a plate-like body A of metal. From one end of the plate is projected toward the other end a spring tongue 6, the side edges 30 of which are shown as spaced from the proximate edges of the body by intervening longitudinal slots 7. The free end of the tongue terminates in a curved edge 8 corresponding to the form desired for trimming 35 of a reed B. Co-operating with this edge of the tongue is an edge 9 of the body, of exactly the same contour and closely adjacent thereto. The two curved edges 8 and 9 are adapted to perform a shearing operation 40 upon the reed in a manner which should be perfectly apparent.

The body end proximate to the cutting edges will be referred to as the head of the trimmer. It is preferably rounded and marginally reinforced as at 10 by a plate C suitably flanged for this purpose. On the upper body side these flanges overlie the body to a moderate extent, whereas on the under body side the plate is provided with inward 45 extensions whereon are carried a pair of ears 11 disposed upwardly, one through each slot 7. The forward edge of each ear may abut the corresponding edge of the associated slot 7 whereby the reinforcing plate C is

locked to the body, irrespective of any clamping engagement therewith which is afforded by its flanged marginal edge.

Extending between the two ears 11 is a pivot pin 12. Mounted for hinge movement on this pin is a cam 14 having spaced downwardly depending ears 15 through which the pivot pin is also extended. Between the two inner ears 15 the cam is formed with a concave edge 16 adapted to bear down with an increasing pressure upon the free end 60 of the tongue. This action is brought about by rotating the cam through the medium of a rearwardly extending handle 17 formed integrally with the cam. If the handle be moved through an arc of 90 degrees, or 65 thereabouts, the cam will force the free end of the tongue into flush relationship with the trimmer body, thereby causing the reed end, if positioned as shown in Figs. 1 and 70 3, to be sheared. The tongue is preferably 75 offset at 18 in the region of its juncture with the trimmer body, the purpose being to permit the tongue to lie substantially parallel with the body at the moment the shearing operation commences. This I have found 80 to be very advantageous in that it contributes to uniformity in the shearing operations.

It is to be noted that the present trimmer comprises but three parts—(1) a body, with which is associated an integral tongue, (2) 85 an operating cam therefor, and (3) a reinforcing plate which strengthens the trimmer head and provides a mounting for the cam. Over long periods of use I have found the present reed trimmer to operate with entire satisfaction, it may be produced at small 90 expense, and its size and weight is such that it may be conveniently carried about for use whenever necessary.

I claim:

1. In a reed trimmer, the combination of an elongated body having a pair of spaced longitudinal slots between which is extended a spring tongue connected at one end integrally with the body, a pair of ears extended through the slots adjacent the ends thereof which are remote from the tongue connection with the body, means connecting the two ears having a clamping engagement with one body end, a cutting edge on the 100 body closely adjacent to and formed in conformity with the edge on the free tongue end, and a cam device pivoted between the 105

2
two ears adapted to move the tongue in a manner to perform a shearing operation, substantially as described.

2. A reed trimmer having a sheet metal body formed with a pair of spaced slots between which is a spring tongue connected at one end integrally with the body, the tongue in the region of such connection being offset whereby it normally occupies a plane different from that of the body, the body at its opposite end being provided with a cutting edge adapted to co-operate with the proximate edge on the free end of the tongue, cam means for moving the free end of the tongue into a plane which is coincident with that of the body to perform a shearing operation, and a single device which provides a mounting for the cam and a reinforcement for

the cutting end of the trimmer, substantially as described.

3. A trimmer comprising three parts (1) a body formed with a pair of spaced slots between which is extended a spring tongue connected at one end integrally with the body, (2) a plate having a marginal engagement with the opposite body end and a pair of ears extended through the slots adjacent the proximate end thereof, whereby the plate is secured immovably to the body, and (3) a cam device pivoted between the ears and adapted to bear with pressure upon the free end of the tongue whereby a shearing operation may be performed, substantially as described.

GEORGE A. FINDER.
